US0D1109722S

(12) **United States Design Patent** (10) Patent No.: **US D1,109,722 S**
(45) Date of Patent: ** Jan. 20, 2026

(54) **WIRELESS EARBUD**

(71) Applicant: **Nothing Technology Limited**, London (GB)

(72) Inventors: **Bin Huang**, London (GB); **Hang Du**, London (GB); **Wenjiao Dai**, London (GB); **Wen Lee**, London (GB); **Shuo Liu**, London (GB)

(73) Assignee: **Nothing Technology Limited**, London (GB)

(**) Term: **15 Years**

(21) Appl. No.: **35/522,875**

(22) Filed: **Oct. 21, 2024**

(80) **Hague Agreement Data**

Int. Filing Date: **Oct. 21, 2024**
